CLAIM

The ornamental design for a lighting fixture, as shown and described.

DESCRIPTION

FIGS. 1-6 are drawings of a first embodiment of the lighting fixture in which FIG. 1 is a right, front, top perspective view of the fixture, FIG. 2 is a left, front, bottom perspective view, FIG. 3 is a left side view, FIG. 4 is a front view, FIG. 5 is a top view and FIG. 6 is a bottom view. Except for the screws (unclaimed) on the central pole from which the fixture is suspended, this embodiment has front-to-rear and left-to-right mirror-image symmetry.

FIGS. 7-13 are drawings of a second embodiment of the lighting fixture in which FIG. 7 is a left, front, top perspective view of the fixture, FIG. 8 is a right, front, bottom perspective view, FIG. 9 is a left side view, FIG. 10 is a front view, FIG. 11 is a right side view, FIG. 12 is a top view and FIG. 13 is a bottom view. This embodiment has front-to-rear mirror-image symmetry; and,

FIGS. 14-20 are drawings of a third embodiment of the lighting fixture in which FIG. 14 is a left, front, top perspective view of the fixture, FIG. 15 is a right, front, bottom perspective view, FIG. 16 is a front view, FIG. 17 is a left side view, FIG. 18 is a right side view, FIG. 19 is a top view and FIG. 20 is a bottom view. This fixture has front-to-rear mirror-image symmetry.

The broken lines shown on the drawings illustrate portions of the lighting fixture which form no part of the claimed design.
